UNITED STATES PATENT OFFICE.

THOMAS J. BRUCE, OF MAYBURG, PENNSYLVANIA.

DESIGN FOR A PICTURE-HANGER.

SPECIFICATION forming part of Design No. 30,179, dated February 14, 1899.

Application filed January 16, 1899. Serial No. 702,361. Term of patent 3½ years.

To all whom it may concern:

Be it known that I, THOMAS J. BRUCE, a citizen of the United States, residing at Mayburg, in the county of Forest and State of Pennsylvania, have invented and produced a new and original Design for Picture-Hangers; and I do hereby declare the following to be a full, clear, and exact description of the same, reference being had to the accompanying drawings, forming a part thereof.

This invention relates to a design for a picture-hanger; and it consists of the essential arrangement and contour of parts, as will be more fully hereinafter described.

The invention is illustrated in the accompanying drawings, in which—

Figure 1 is a perspective view of a picture-hanger embodying the design. Fig. 2 is a side view of the same.

Referring now more particularly to the drawings, wherein like letters of reference designate corresponding parts throughout both views, A represents the upper portion

of the hanger, which consists of a plate having its upper end curved and turned down to form a hook B.

The lower portion of the hanger, embodying the essential features of my design, comprises a reduced stem C, provided at its free end with oppositely-projecting lateral arms d d and a lower pendent arm d', which form in conjunction therewith a cross-shaped hanger or suspending member E. These arms may be apertured, as shown, for the reception of hooks.

Having thus described my invention, I claim—

The design for a picture-hanger, substantially as herein shown and described.

In testimony whereof I affix my signature in presence of two witnesses.

THOMAS J. BRUCE.
